(74) Attorney, Agent, or Firm — Kilpatrick Townsend & Stockton LLP

(57) **CLAIM**

The ornamental design for video conference remote control, as shown and described.

DESCRIPTION

FIG. 1 is a perspective view of our video conference remote control showing our new design;

FIG. 2 is a second perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a right side elevation view thereof; and,

FIG. 8 is a left side elevation view thereof.

The broken lines shown in the drawings form no part of the claimed design.

1 Claim, 3 Drawing Sheets(56)
